UNITED STATES PATENT OFFICE.

HEINRICH ZWICKY, OF SCHINDELLEGI, SWITZERLAND.

WEFT-REPLENISHING MECHANISM FOR LOOMS.

No. 926,918.

Specification of Letters Patent.

Patented July 6, 1909.

Application filed February 3, 1908. Serial No. 414,048.

To all whom it may concern:

Be it known that I, HEINRICH ZWICKY, a citizen of the Republic of Switzerland, residing at Schindellegi, Canton of Schwyz, in Switzerland, have invented certain new and useful Improvements in Weft-Replenishing Mechanism for Looms; and I do hereby declare the following to be a full, clear, and exact description of the invention, such as will enable others skilled in the art to which it appertains to make and use the same, reference being had to the accompanying drawings, and figures of reference marked thereon, which form a part of this specification.

This invention has for its object an apparatus for automatically changing or replacing the weft pirns in looms and comprises a pirn magazine; and a device for removing the pirns from the magazine and inserting these pirns in the shuttles. In devices of this kind hitherto employed, the magazine and the mechanism for removing and inserting the pirns were independent of the lay, and were arranged on the front side of the loom. The insertion in the shuttle of a pirn withdrawn from the magazine had to take place at the moment at which the lay, in the normal working of the loom, had reached its front deadpoint position, and therefore the time for this insertion was extremely brief. If for any reason the lay reached this deadpoint position somewhat prematurely, or somewhat late, the pirn changing mechanism failed to work correctly.

In the mechanism which forms the subject-matter of the present invention, the magazine and the device for removing and inserting the pirns, are mounted on the lay. In this arrangement a relative movement forward of the removing and inserting device to the lay, does not take place, nor to the shuttle while the latter rests in the shuttle box, so that a much longer time is at disposal for the insertion of the pirn.

The object of the invention is shown in one form of construction as an example in the accompanying drawings, Figure 1 being a section on the line A—B of Fig. 2, and Fig.

2 a front elevation, while Fig. 3 is a detail.

The pirn magazine 1 is held over the lay by means of a carrying or supporting arm 2 to which it is attached. This magazine forms a box, open above and below, rising obliquely to the front from the lay, the front and rear walls 1^x having a spring action relative to

one another and to the upper aperture or mouth 1^{xx} which is turned to the front and somewhat contracted. A catch 3 is mounted on the supporting arm 2, which catch is controlled by a spring 4. On the lay, a sector 6 (shown separately in Fig. 3) is located in such a way as to be pivotal on an axis 6^x, which sector has to right and left, on its upper end 7, forked projections 8, 9 and on the side a pin 11.

13 is a rod, one end 12 of which, is forked, and the other end 14 of which is connected with a spring 15 arranged on the front side of the loom. This rod 13 rests on a spring 16 79 which is attached to the boss 17 of a lever arm 18, against which a bar 19 belonging to the ordinary weft guard device of the loom, rests.

20 is a spiral spring one end of which is attached to the sector 6 and the other to the lay. The movement of the sector, which this spring tends to produce, is limited by a regulating screw 21 which serves as a stop for the sector.

5 are full pirns lying in the magazine. The lowermost of these pirns is carried by the forked projections 8 and 9 of the sector 6 and held on the segment by the catch 3 pressing against them.

22 are two clamp disks lying against one another, between which the ends of the threads of the pirns 5 are held.

The mode of action of the pirn changing mechanism hereinbefore described is as follows: On the breakage of a thread, or the exhaustion of the weft thread, the rod 19, and by it the lever 18, are moved by the thread guard device, in the direction indicated by the arrow, which consequently lifts 95 the rod 13. The pin 11 which otherwise can pass the rod 13, then encounters the forked end 12 of the rod, on the movement of the lay into its front deadpoint position. By the pin 11 encountering the rod 13, the sector 6 is swung out in the direction indicated by the arrow and conveys the pirn carried by the projections 8, 9 into the shuttle thereby pushing aside the catch 3, and expelling the pirn located in the shuttle, which drops out 100 downward through an aperture in the lay. During this swinging out of the sector, the catch 3 forms a guide for the pirn, retained by the projections 8 and 9, from the magazine to the shuttle. Then when the lay

110 swings back, the sector is moved back into its initial position by means of the spiral

spring 20, and the catch 3 by means of the spring 4. The pirns lying in the magazine slip downward and the lowermost of them assumes the position of the one which has been inserted in the shuttle. By the rod 13 being mounted on a spring, the force of the shocks when the pin 15 encounters the end 13 of the rod, is somewhat mitigated.

A pirn may be inserted in the magazine 16 during the movement of the lay by holding this pirn in the path of the upper opening or mouth of the magazine. On the swinging forward of the lay, the magazine, the upper end of which forms a jaw or mouth, seizes 15 this pirn and takes it with it.

A bar 23 is arranged in the magazine, which bar engages behind the head of the rear end of the pirn spindles and is intended to prevent the pirns in the magazine vibrating during the reciprocation of the lay.

The pirn magazine may be only loosely inserted in the socket at the upper end of the carrying arm, in order to allow of its being removed from the carrying arm and filled 25 with pirns away from the loom. Such a magazine may be inserted in the socket of the carrying arm during the movement of the lay, in similar manner, to the example shown, when a pirn is inserted in the magazine; the 30 socket of the carrying arm in this case is preferably made expandible and its upper aperture tapering outwardly, in order to facilitate the insertion of the magazine. Such a construction is particularly adapted for rapid 35 running looms.

In place of the two clamp disks 22 any other suitable device for holding the thread ends may be provided, for instance a roller with a card clothing. The arrangement 40 shown has however the advantage of great simplicity and it may be easily applied to already existing looms.

Having now particularly described and ascertained the nature of my said invention 45 and in what manner the same is to be performed, I declare that what I claim is:

1. In an automatic weft replenishing mechanism for looms the combination with the lay; of a pirn magazine mounted on the lay, 50 a device also mounted on the lay to seize and carry a pirn from the magazine to the shuttle and mechanism to actuate said device.

2. In an automatic weft replenishing mechanism for looms the combination with the 55 lay; of a pirn magazine mounted on the lay and a sector also pivotally mounted on the lay to seize the lowermost pirn in the magazine and insert it in the shuttle and simultaneously expel the pirn or pirn spindle in the 60 shuttle.

3. In an automatic weft replenishing mechanism for looms the combination with the 65 lay; of a pirn magazine mounted on the lay, a pivotally mounted sector also on the lay and means to engage and rotate the sector, said

means controlled from the weft detecting mechanism of the loom.

4. In an apparatus in looms for automatically changing the weft pirns, a pirn magazine and a pivotally mounted sector for removing the pirns therefrom and inserting them in the shuttles, the pirn magazine and the sector being mounted on the lay and the latter having forked projections supporting the lowermost pirn in the magazine.

5. In an apparatus in looms for automatically changing or replacing the weft pirns, a pirn magazine and a pivotally mounted sector for removing the pirns therefrom and inserting them in the shuttles, the pirn magazine and the sector being mounted on the lay and a spring catch under the magazine to hold the pirn in position as it is carried by the sector to the shuttle.

6. In an automatic weft replenishing mechanism for looms the combination with a lay; of a pirn magazine mounted on the lay, a spring catch at the end of the magazine, a sector also mounted on the lay and having forked projections and means to actuate the 90 sector, said sector and spring catch co-operating to guide a pirn to the shuttle.

7. In an automatic weft replenishing mechanism for looms the combination with a lay; of a socket mounted on the lay, a pirn magazine having a contracted spring mouth 95 mounted in the socket and means to move a pirn from the magazine and insert it in the shuttle.

8. In an automatic weft replenishing mechanism for looms, the combination with a lay; of a socket mounted on the lay, a forwardly projecting pirn magazine having a contracted spring mouth and mounted in the socket, 100 said magazine and socket forward of the raceway in the lay and means to take a pirn from the raceway and insert it in the shuttle.

9. In an automatic weft replenishing mechanism, for looms the combination with a lay; of a socket mounted on the lay, a removable 110 pirn magazine in the socket, a spring controlled sector pivotally mounted on the lay and having lateral forked projections, said projections engaging the lowermost pirn in the magazine and means controlled by the 115 weft detecting mechanism of the loom to move the sector, said sector during its movement closing the bottom of the magazine.

10. In an automatic weft replenishing mechanism for looms, the combination with the lay; of a pirn magazine and a sector, both mounted on the lay, a pin on the sector, and a pivoted rod, and means controlled by the 120 weft detecting mechanism of the loom to move the end of the rod in the path of said pin to move the sector and cause it to remove a pirn from the magazine into the shuttle.

11. In an automatic weft replenishing mechanism for looms, the combination with the lay; of a pirn magazine and a spring re-

tracted sector, both mounted on the lay, a pin on the sector, a pivoted spring supported arm having a forked end and mechanism controlled by the weft detector of the loom to move said arm into the path of said pin.

12. In an automatic weft replenishing mechanism for looms, the combination with the lay, of a socket having a spring catch thereon, a removable inclined pin magazine therein, a spring retracted sector having forked projections, said sector, socket and magazine forward of the shuttle race, a pin

on the sector, a spring supported pivoted arm having a forked end and means operated by the weft detector of the loom to move the 15 arm to cause its forked end to engage said pin.

In testimony that I claim the foregoing as my invention, I have signed my name in presence of two subscribing witnesses.

HEINRICH ZWICKY.
